UNITED STATES PATENT OFFICE.

CHARLES H. BROWN, OF LILLY, PENNSYLVANIA.

RAIL-TIE.

No. 826,400.

Specification of Letters Patent.

Patented July 17, 1906.

Application filed March 27, 1906. Serial No. 308,298.

To all whom it may concern:

Be it known that I, CHARLES H. BROWN, a citizen of the United States, residing at Lilly, in the county of Cambria and State of Pennsylvania, have invented certain new and useful Improvements in Rail-Ties, of which the following is a specification.

This invention relates to railway-ties, the object of the invention being to provide a practical, cheap, and reliable metallic railway-tie having novel means for anchoring and for keying the ballast in place, and, further, provided with means whereby the rails may be spiked to the tie in a manner similar to that employed in connection with wooden ties.

With the above and other objects in view, the nature of which will more fully appear as the description proceeds, the invention consists in the novel construction, combination, and arrangement of parts hereinafter more fully described illustrated, and claimed.

In the accompanying drawings, Figure 1 is a vertical longitudinal section through a metallic railway-tie embodying the present invention. Fig. 2 is an end view of adjacent ties, showing the rail ends supported thereon. Fig. 3 is a top plan view of the tie, omitting the rails. Fig. 4 is a vertical cross-section through the tie, taken in line with the spike-plugs. Fig. 5 is a sectional view of the tie, showing the keys.

The tie contemplated in this invention comprises a metallic body, which may be either cast or made out of sheet metal of the requisite gage to give the necessary stiffness, the tie comprising the imperforate bottom 1, sides 2, and the top 3, which is also imperforate with the exception of a plurality of openings formed therein to receive the spike-plugs. The tie is thus practically continuous in cross-section and is adapted to receive a ballast filling of concrete, as shown at 4, and in order to hold said concrete filling in place while still in a plastic condition the tie is provided at each extremity thereof with an inwardly-extending flange 5, extending around the bottom and sides of the tie and adapted to receive within it a slide or closure 6, which is inserted through an opening 7 in the top of the tie in line with the inner face of the flange 5, as clearly shown in Figs. 2 and 3. The slides or closures 6 prevent the filling 4 from finding its way out of the tie, and thus the

tie may be filled with the composite ballast 55 until every portion of the interior thereof is taken up.

Extending inward from each side of the tie is a key 8 in the form of a flange having the inner edge thereof turned downward, as 60 shown at 8', the keys 8 being arranged opposite each other in the same horizontal plane. Between the keys 8 and extending upward from the center of the bottom of the tie is another key 9 in the form of a flange the upper edge of which is cut downward at suitable intervals, the portions intervening between the cuts being bent over in opposite directions, as at 9', to extend laterally toward the downturned inner edges of the keys 70 8, as clearly shown in Fig. 4.

If desired, the inner edges of the keys 8 may be cut at intervals like the key 9 and the intervening portions between the cuts bent in opposite directions, some to extend 75 upward and some to extend downward, as shown in Figs. 4 and 5. The keys just described extend into the filling, obtaining a firm hold thereon and anchoring the filling and tie firmly together. 80

Adjacent to each end the tie is provided in the top thereof with a series of openings 10 of suitable size to receive metallic sockets or plug-holders 11, in which are driven wooden plugs 12, adapted to receive the spikes 13, by 85 which the rails 14 are secured to the tie, as shown in Fig. 1. Two of such spike-plugs 12 are arranged at each side of each rail under the preferred embodiment of this invention, and the plugs are securely anchored to the tie 90 by threading or roughening the outer surfaces of the plug-holders 11, as indicated in Figs. 1 and 4, so that the filling 4 will engage such threads or rough places and when hard obtain a firm hold on said sockets or plug-holders. 95

From the foregoing description it will be seen that the rails may be spiked to the tie in a manner similar to that in which rails are now usually fastened to the ordinary wooden tie. It will also be seen that the ballast or filling of the tie is prevented from shifting by means of the keys hereinabove described, and, further, that the ballast is prevented from escaping from the interior of the tie by 105 means of the end closures or slides.

I claim—

1. A hollow metallic railway-tie compris-

ing a top, bottom and sides, the bottom and sides being provided with end flanges, and removable, closures or slides fitted to the tie and held within said end flanges.

5. A hollow metallic railway-tie comprising a top, bottom and sides, the bottom and sides being provided with inwardly-extending end flanges and the top being provided with a slot or opening in line with the inner faces of said flanges, and sliding closures removably fitted behind said flanges.

10. 3. A hollow metallic railway-tie comprising a hollow body, and a key extending from the bottom upward within the tie and having its upper edge deflected laterally.

15. 4. A hollow metallic railway-tie comprising a hollow body, and a key extending from the inner wall of the tie inward and having the inner edge thereof cut or divided, the divided portions thereof being deflected in opposite directions.

20. 5. The combination with a hollow metallic

25. railway-tie, of spike-receiving plugs inserted in the top thereof, substantially as described.

6. The combination with a hollow metallic railway-tie, and a composite filling therein, of spike-receiving plugs extending from the top of the tie inward, and plug-holders embracing said plugs and anchored in the filling.

30. 7. The combination with a hollow metallic railway-tie having openings in the top thereof, and a composite filling within the tie, of metallic sockets or plug-holders inserted through the top of the tie and having their outer faces roughened for engagement with the filling of the tie, and spike-receiving plugs held within said metallic sockets or plug-holders.

35. In testimony whereof I affix my signature in presence of two witnesses.

CHARLES H. BROWN.
